UNITED STATES PATENT OFFICE

2,419,638

HANGER

Alfred Graeber, Milwaukee, Wis.

Application January 11, 1946, Serial No. 640,577

2 Claims. (Cl. 223—95)

1

This invention relates to improvements in hangers, and more particularly to improved hangers of the type adapted to hang trousers from the cuff ends.

An object of the invention is to provide a device of the type which will suspend trousers from the cuff ends thereof in a manner which will distend the cuffs and hang the trousers with straightened lines tending to eliminate all wrinkles.

Another object of the invention is to provide a device of the type which may quickly and easily be attached to the trousers for the hanging thereof.

Another object of the invention is to provide a device for hanging trousers by the cuffs which will not tend to press new and objectionable lines or wrinkles into the garment as is the case with cuff hangers of types now in use.

Other and further objects of the invention will appear as the description proceeds, reference being had to the accompanying drawing, in which:

Fig. 1 is a view in perspective of a pair of trouser hangers embodying my invention.

Fig. 2 is a view in perspective of a removable pusher head.

Fig. 3 is a view partly in elevation and partly in section showing the spring mechanism.

Fig. 4 is a view in perspective of a modified form of the invention.

Fig. 5 is a fragmentary detail view partly in elevation and partly in section showing a removable pusher head for the modified form.

Referring more particularly to the drawings, as shown in Fig. 1, each of the hangers is exactly the same, having a body portion 10 suspensable by a hook 11, and having a stationary end member 12. The body 10 is slotted at 13 to accommodate the pin 14 which is inserted in a boring at 15 of the pusher rod 16 which latter carries the removable pusher head 17. As shown in Fig. 3 the pusher rod 16 is pressed outwardly by the coil expansion spring 18. The pusher rod 16 has the threaded member at 19 to provide for attachment of pusher heads 17 of various lengths one of which is shown in Fig. 2.

In the modified form of the invention shown in Fig. 4, a body portion 25 has the hook member 26 for suspending the unit, and the fixed member 27 with two downwardly directed leaves 28 and 29. Body portion 25 is slotted at 30 to accommodate the pin 31 which is insertable in borings 32 of the pusher rod 33, which latter carries the pusher head 34 provided with the

2

retractor handle 35 and the downwardly directed leaves 36 and 37. Various sizes of pusher heads 34 are provided and are threadingly engaged with the pusher rod 33 as shown in Fig. 5.

5 In use, a plurality of variously sized pusher heads 17 are provided, and the one of appropriate size is attached, according to the dimensions of the cuffs of trousers or the waistband of the skirt to be hung. The head 17 is retracted by manual 10 operation, and the device is then inserted into the cuff of the inverted trousers or other garment. Release of the head 17 will provide an expanding tension of the parts sufficient to retain the garment. One of the devices is inserted into each 15 cuff and the whole suspended, as in a clothes closet, by means of the hooks 11.

In use of the preferred form, a unit is provided for each cuff, but in the modified form of the invention illustrated in Fig. 4, a single unit accommodates both cuffs of the trousers, one cuff being stretched over the downwardly directed leaves 36 and 28, and the other cuff enveloping the leaves 37 and 29. The expanding spring pressure will retain the trouser cuffs thereon.

25 The hangers may very easily be used to suspend skirts by attachment within the waistbands thereof, and to accommodate very large skirts it would only be necessary to attach a relatively long pusher head 17, or to lengthen the body 30 portion 10.

It will be understood that the device is capable of many modifications in structure and design, without departing from the spirit of the invention, within the scope of the appended claims.

35 Having thus described my invention, what I claim and desire to secure by Letters Patent of the United States, is:

40 1. A garment hanger comprising a body portion having a bore longitudinal thereof and square in cross section at one end, a threaded longitudinal stud projecting from its opposite end, a garment engaging member having a square shank slidable in said square bore, a square enlargement adjacent the outer end of said shank as a stop and terminating outwardly in a vertically flared and reduced blunt edge disposed vertically for contact with the inside of a garment, a like member for the opposite end having a threaded bore in its inner end for engaging with 45 said stud for adjustment thereon longitudinally relative to said body, spring means for urging said shank outwardly of said body, the said body having a longitudinal slot in its top over said shank, and a pin fixed in the top of said shank 50 extending upwardly through said slot to limit 55

outward movement of the shank and for use as a gripping member.

2. A garment hanger comprising a horizontal body portion having a longitudinal bore at one end, a threaded stud projecting longitudinally from the other end, a garment engaging member having a threaded bore for engagement with said stud for longitudinal adjustment thereon, a second garment engagement member, a shank integral therewith slidable in said bore and having spaced transverse bores therein, the said body being provided with a lateral longitudinal slot adjacent said shank, a pin engageable in any of the transverse bores of the shank extending through said slot to limit outward movement of the shank, 15 spring means in said body for outward urging of said shank, and a member integral with and extending upwardly of said second garment engaging member to serve as a gripping means to com-

press the device prior to insertion thereof into a garment.

ALFRED GRAEBER.
